UNITED STATES PATENT OFFICE.

CHARLES DOESCHER, OF WATERBURY, CONNECTICUT.

DESIGN FOR A MATCH-BOX.

SPECIFICATION forming part of Design No. 30,981, dated June 18, 1899.

Application filed May 16, 1899. Serial No. 717,099. Term of patent 7 years.

To all whom it may concern:

Be it known that I, CHARLES DOESCHER, of Waterbury, in the county of New Haven and State of Connecticut, have invented and produced a new Design for a Match-Box; and I do hereby declare the following, when taken in connection with the accompanying drawing and the letters of reference marked thereon, to be a full, clear, and exact description of the same, and which said drawing constitutes part of this specification, and represents a perspective view of a match-box embodying my design.

This invention relates to a design for a match-box. As shown in the drawing, the leading or material feature of my design is a match-box having four openings or holes *a b c d* in one face *A* of the box *B*. As herein

shown, the holes are arranged at the angles of a square, the holes *a c* being in a plane longitudinally through the center of the box and the holes *b d* in a central plane laterally through the box.

Having fully described my invention, what I claim as new, and desire to secure by Letters Patent, is—

The design for a match-box as herein shown and described.

In testimony whereof I have signed this specification in the presence of two subscribing witnesses.

CHARLES DOESCHER.
